RAZOR MAGAZINE

George Douglas Jones and Leonidas C. Miller, Los Angeles, Calif., assignors to Reelshav Corporation, Los Angeles, Calif., a corporation of California

Application September 14, 1950, Serial No. 12,182

Term of patent 14 years

(Cl. D58—12)

To all whom it may concern:

Be it known that we, George Douglas Jones and Leonidas C. Miller, citizens of the United States of America, residing at Los Angeles, in the county of Los Angeles and State of California, have invented a new, original, and ornamental Design for a Razor Magazine, of which the following is a specification, reference being had to the accompany drawings, forming a part thereof.

Figure 1 is a perspective view, showing our new design for a razor magazine.

Figure 2 is an end elevation of our razor magazine.

Figure 3 is a rear elevation of our razor magazine.

Figure 4 is a top plan view of our razor magazine.

We claim:

The ornamental design for a razor magazine, substantially as shown.

GEORGE DOUGLAS JONES.
LEONIDAS C. MILLER.
